US0D1084092S

(12) **United States Design Patent** (10) Patent No.: **US D1,084,092 S**
(45) Date of Patent: ** Jul. 15, 2025

(54) **CAMERA MOUNT**

(71) Applicant: **Amazon Technologies, Inc.**, Seattle, WA (US)

(72) Inventors: **Wen-Yo Lu**, Pasadena, CA (US); **Matthew J. England**, Santa Monica, CA (US); **Chia-Song Liu**, Hsinchu (TW); **Tsung-Kai Cheng**, Taipei (TW); **Ming-Cheng Cheng**, Taoyuan (TW); **Oleksii Krasnoshchok**, Gdynia (PL); **Oleksii Shekolian**, Kyiv (UA); **Sergiy Aafanasov**, Seattle, WA (US); **Mikhail Donskoi**, Brovary (UA); **Chia-Wei Chan**, Taipei (TW)

(73) Assignee: **Amazon Technologies, Inc.**, Seattle, WA (US)

(**) Term: **15 Years**

(21) Appl. No.: **29/982,058**

(22) Filed: **Jan. 3, 2025**

Related U.S. Application Data

(63) Continuation of application No. 29/939,749, filed on Apr. 29, 2024, now Pat. No. Des. 1,064,033.

(57) **CLAIM**

The ornamental design for a camera mount, as shown and described.

DESCRIPTION

FIG. 1 is a top, front, right-side perspective view of a camera mount;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the camera

mount that form no part of the claimed design.

1 Claim, 8 Drawing Sheets
